UNITED STATES PATENT OFFICE.

PHILO W. MILLER, OF GRAND JUNCTION, IOWA.

DESIGN FOR A PICTURE-HANGER.

SPECIFICATION forming part of Design No. 16,207, dated August 18, 1885.

Application filed May 26, 1885. Term of patent 7 years.

To all whom it may concern:

Be it known that I, PHILO W. MILLER, a citizen of the United States, residing at Grand Junction, in the county of Greene and State 5 of Iowa, have invented and produced a new and original Design for a Picture-Hanger, of which the following is a specification, reference being had to the accompanying drawing, forming a part thereof.

10 The leading feature of my design consists of a disk or plate having an approximately annular top in outline, and a crescent-shaped lower portion provided with a grooved lip or flange on the inner edge thereof, which constitutes the segment of a circle.

As shown in the drawing, the approximately annular top has a perforation through which the nail passes in depending the design from the wall, and the segmental groove or

lip is on the lower edge and receives the cord 20 in adjustment, as shown, presenting only an unbroken, continuous segmental line having no acute or obtuse angles. The design is thus pleasing to the eye and useful in ornamentation.

Having described my invention, what I desire to secure by Letters Patent is—

The design for a picture-hanger as herein shown and described, the same consisting of a disk or plate having an approximately annular top in outline, a crescent-shaped lower portion, and a grooved lip or flange on the edge thereof, which constitutes the segment of a circle.

PHILO W. MILLER.
